DESIGN FOR A DRILL HOLDER

William P. Ross, Lakewood, Ohio, assignor to The Standard Tool Co., Cleveland, Ohio, a corporation of Ohio

Application April 13, 1939, Serial No. 84,265

Term of patent 14 years

To all whom it may concern:

Be it known that I, William P. Ross, a citizen of the United States, residing at Lakewood, in the county of Cuyahoga and State of Ohio, have invented a new, original, and ornamental Design for Drill Holder, of which the following is a specification, reference being had to the accompanying drawing, forming a part thereof.

In the drawing, Figure 1 is a plan view of a drill holder embodying my new design,

Figures 2 and 3 are end and front elevational views, respectively, thereof.

I claim:

The ornamental design for a drill holder, substantially as shown.

WILLIAM P. ROSS.
